ATTORNEY

UNITED STATES PATENT OFFICE.

ALBERT SCHREIBER, OF CHAMPAIGN, ILLINOIS.

MOP.

Application filed March 19, 1926. Serial No. 95,958.

This invention relates to improvements in mops, the general object being the provision of a pair of companion looped frames secured within the forward end of a mop handle for the reception of a portion of a mop rag and having an adjustable clamping means arranged between their corresponding inner sides for securing a portion of the mop rag within their looped portions where-
5 by the latter may be held against accidental displacement while in use.

With the above and other objects in view, the invention further includes the following novel features and details of construction, 15 to be hereinafter more fully described, illustrated in the accompanying drawings and pointed out in the appended claims.

In the drawing:

Figure 1 is an elevation of the invention.
20 Figure 2 is a top plan view thereof.

Figure 3 is a longitudinal sectional view of the invention.

Figure 4 is a top plan view of the invention with the adjustable clamping means 25 released from its normal positions as illustrated in Figures 1 and 2 of the drawings.

Figures 5 and 6 are vertical sections taken on lines 5—5 and 6—6 respectively on Figure 2.

30 Figure 7 is a perspective of the adjustable clamping means per se.

Figure 8 is a perspective of a locking plate.

Referring to the drawings in detail, where-
35 in like characters of reference denote cor-
responding parts, the reference character 10
indicates a mop handle having a ferrule 11
secured to its forward end and terminating
in a rectangular shaped forward end por-
40 tion 12 as illustrated in Figure 6 of the
drawings and adapted to receive within its
respective corners and against the outer
sides and forward end of the mop handle
10 the spaced parallel inwardly extending
45 end portions 13 of companion frames 14
defining transversely disposed elongated
looped portions within the outer ends and in
general resembling a substantial T-shape.
Such frames being formed of twisted lengths
50 of wire, the purpose of such construction be-
ing readily apparent.

The adjustable clamping means constituting
a relatively flat substantially T-shaped
55 plate 16 providing oppositely and obliquely
disposed cutout portions 17 upon its forward
edge and adjacent its opposite ends and

adapted for longitudinal sliding movement
between the corresponding inner sides of the
companion frames 14, while its vertical leg
providing spaced parallel upwardly extend-
ing guide plates 18 upon its opposite side
edges which extend appreciable distances
above and below the upper and lower sides
thereof for guiding the said plate 16 be-
tween the corresponding inner sides of the
companion frames 14 and for engagement
with the outer sides of the inwardly extend-
ing end portions 13 thereof. The outer side
guide plates 18 defining concaved portions
19 in providing a convenient gripping means
for facilitating a sliding movement to the
relatively flat substantially T-shaped lock-
ing plate 16. The inner end of the plate
16 has an opening 20 provided therein, with-
in which a bolt such as indicated at 21 ex-
tends therethrough and in like manner
through registering openings 22 provided
centrally within companion locking plates
23 arranged upon the upper and lower sides
of the plate 16 and defining and providing
enlarged portions 24 extending longitudi-
nally thereof upon their inner sides whereby
the inwardly extending end portions 13 of
the companion frames 14 may be also held
in spaced parallel relationship therebetween.
25 The opposite end of the bolt 21 having a
wing nut 25 threaded thereon whereby rela-
tive movement may be imparted to the com-
panion locking plates 23 between the guide
plates 18 and against the outer sides of the
30 inwardly extending end portions 13 of the
companion frames 14.

In the use and operation of the present in-
vention, it is clearly apparent and manifest
that the substantially T-shaped plate 16
when arranged in the position as clearly il-
lustrated in Figure 4 of the drawings will
permit the insertion of a mop rag or squee-
gee such as indicated at 26 to be inserted
within the elongated looped portions 15 de-
fined in the transversely disposed end por-
tions of the substantially T-shaped com-
panion frames 14 and upon an outward slid-
ing movement of the relatively flat substan-
tially T-shaped locking plate 16 between the
corresponding inner sides of the companion
frames 14 and in their respective positions as
illustrated in Figures 1 and 2 of the draw-
ing will force an appreciable portion of the
mop rag 26 outwardly and between the
frames 14 and upon tightening the nut 25
upon the free end of the bolt 21 will rigidly
100
105
110

tension the outer ends of the frames 14 downwardly and inwardly upon the mop rag 26 and against the head of the substantially T-shaped locking plate 16 whereby such rag 5 will be held against accidental displacement during the process of mopping. The configuration of the companion frames 14, being formed from twisted lengths of suitable wire offering and presenting an irregular 10 surface to the mop rag 26 in order that the latter when dampened may not slide between the inner gripping sides.

The invention is susceptible of various changes in its form, proportions and minor 15 details of construction, and the right is herein reserved to make such changes as properly fall within the scope of the appended claims.

Having thus described the invention, what 20 is claimed is:—

- 25 1. A mop of the character described comprising a handle, a ferrule carried upon the forward end thereof, companion frames fitted upon the handle within the ferrule, a clamping plate slidably positioned between the frames, and interconnected locking plates carried upon the frames for holding the clamping plate at a desired position between the frames.
- 30 2. A mop of the character described comprising a handle, frames carried upon the forward end thereof, a clamping plate positioned for longitudinal sliding movement between the frames, guide members carried by the locking plate to receive a portion of the frames therebetween, and locking plates positioned between the guide plates and adapted for engagement with the frames for re-

taining the clamping plate against displacement.

3. A mop comprising a handle, frame members of substantial T-shaped configuration providing elongated looped portions within their forward ends and having spaced legs carried upon one end of the handle, a T-shaped clamping plate adapted for sliding movement between the frame members, guide plates carried upon the opposed sides of the clamping plate and receiving appropriate portions of the frame members therebetween, and locking means positioned between the guide plates for biting engagement with the frame members to sustain the clamping plate in a desired position.

4. A mop comprising a handle, frame members of substantial T-shaped formation providing looped portions at their forward ends, said members having legs disposed in spaced parallel relation rearwardly thereof and carried upon the forward end of the handle, a correspondingly shaped clamping plate having guide plates upon the opposed side edges of the leg and receiving portions of the legs of the frame members therebetween, locking plates fitted between the guide plates upon the opposed sides of the clamping plate, said locking plates providing shoulders upon their inner sides adapted for biting engagement with the legs of the frame members, and a bolt carried by the locking plates and passed through said clamping plate whereby the latter may be rigidly held in a desired adjusted position.

In testimony whereof I affix my signature.

ALBERT SCHREIBER.
